UNITED STATES PATENT OFFICE.

JOHN S. McWHIRTER, OF NEW YORK, N. Y., ASSIGNOR TO WESTINGHOUSE ELECTRIC & MANUFACTURING COMPANY, A CORPORATION OF PENNSYLVANIA.

CONTROL APPARATUS.

Application filed June 9, 1919. Serial No. 302,664.

To all whom it may concern:

Be it known that I, JOHN S. McWHIRTER, a citizen of the United States, and a resident of New York, in the county of New York and State of New York, have invented a new and useful Improvement in Control Apparatus, of which the following is a specification.

My invention relates to control apparatus for dynamo-electric machines and particularly to platform-mounted control apparatus for electric railway vehicles.

One object of my invention is to provide a foot-operated electric controlling means and a brake-controlling means, preferably the familiar engineer's valve, that is located in substantial alinement with, or in proximity to, the foot-operated mechanism to be actuated thereby.

Another object of my invention is to provide a combined foot-controlled apparatus of the above-indicated type which shall be relatively compact in arrangement, convenient to operate and inexpensive to repair by reason of the relatively small number of necessary parts.

My invention may best be understood by reference to the accompanying drawing, wherein—

Figure 1 is a plan view of a combined control apparatus constructed and arranged in accordance with my present invention;

Fig. 2 is a view, in end elevation, of a portion of the apparatus that is shown in Fig. 1; and

Fig. 3 is a view, in rear elevation, of the complete controlling apparatus.

Referring to the drawing, the structure here shown comprises an electric controlling means 1 which may be of the familiar drum-controller type; a brake-controlling means 2, preferably the well-known engineer's valve for air-brake systems; and an intermediately located foot-operated mechanism 3 for simultaneously governing the electric and the air-brake-controlling apparatus.

The electric controlling means 1 is shown as comprising a drum structure 5 that is rigidly mounted upon an operating shaft 6 and carries suitable contact segments 7 for engaging the desired combinations of control fingers 8, in accordance with familiar practice. For the purpose of biasing the entire mechanism to the illustrated position, wherein emergency-braking operation of

the engineer's valve 2 is provided, a spring 9 is secured to the drum structure 5. The controller is illustrated as having five positions, respectively labeled "Emergency", to which reference has just been made; "Service", corresponding to service application of the air-brakes; "Lap", corresponding to the familiar lap operation of the engineer's valve; "Brake release", for effecting release of the air-brakes before current is supplied to the car-propelling motors; and "Run", corresponding to the acceleration of the motors.

It will be understood that, if desired, the electric controlling means may be of any other type and, for example, may take the form of a simple contact-maker and breaker, as set forth in my co-pending application, Serial No. 277,873, filed February 18, 1919.

The engineer's valve 2 comprises a suitably chambered casing or cylinder 10, with which a plurality of supply and outlet pipes 11 communicate, and the familiar detachable operating handle 12.

It will be understood that the air-brake valve 2 in the present case is adapted to occupy five operative positions corresponding to the five positions of the control drum 5. In this case, the "brake-release" and "run" positions are identical in that no modification of the braking control is effected by moving the engineer's valve beyond the "brake-release" position to the "run" position. However, if the above-mentioned simple contact-maker and breaker is employed as an electric controlling means, the engineer's valve need be provided with only the four usual positions, the "run" position being omitted.

The foot-operating mechanism 3 comprises a preferably detachable pedal or foot-lever 13 that is mounted upon a sleeve 14, which is rigidly secured to the operating shaft 6 by means of a set-screw 15, for example. A suitable pedestal of bearing-block 100 16 supports the outer end of the shaft 6, to which a pin 17 or other suitable means serves to secure one end of a right-angle arm or lever 18, the other end of which is forked or bifurcated to engage the shank of the operating handle 12 for the engineer's valve 2. It will be observed that the engineer's valve 2 is located in substantial alinement with the foot-operated mechanism 3 and requires only the right-angle arm 18 to provide ac-

tuation of the valve in accordance with the movements of the foot-lever 13. If desired, the operating handle 12 for the valve may be omitted, and a direct coupling of the 5 valve rod and the shaft 6 may then be provided.

The operation of the illustrated apparatus may be briefly set forth as follows. Under 10 normal conditions, the apparatus occupies the "emergency-breaking" position, as previously mentioned. Upon the application of foot-pressure to the pedal 13, the apparatus is actuated through its successive positions "Service" and "Lap" to the "brake-release" 15 position, whereby the application of the vehicle brakes is released. Upon further movement of the foot-lever 13, the "run" position of the controller 5 is occupied to effect electric control of the car-propelling motors in 20 any suitable manner, which need not be described in detail here.

It will be understood that the structural details and arrangement of parts herein shown may be modified to meet particular 25 operating conditions without departing from the spirit and scope of my invention. I desire, therefore, that only such limitations shall be imposed as are indicated in the appended claims.

30 I claim as my invention:

1. In a vehicle, the combination with electric controlling means and foot-operated means for governing said controlling means, of brake-controlling means located in substantial axial alinement with said foot-operated means to be actuated thereby.

2. In a vehicle, the combination with electric controlling means and foot-operated means for governing said controlling means, 40 of an air-brake-controlling valve located in substantial axial alinement with said foot-operated means to be actuated thereby.

3. In a vehicle, the combination with electric controlling means and a foot-operated 45 member for governing said controlling means, of graduated air brake-controlling means located in proximity to said foot-operated member, and single means for mechanically connecting said brake-controlling means and said foot-operated member.

4. In a vehicle, the combination with electric controlling means and a foot-operated member for governing said controlling means, of an air-brake-controlling valve located in proximity to said foot-operated member, and means for mechanically connecting said valve and said foot-operated member.

5. In a vehicle, the combination with electric 60 controlling means and a foot-operated

member for governing said controlling means, of brake-controlling means having a horizontally-extending operating member, and single means for mechanically connecting said members. 65

6. In a vehicle, the combination with electric controlling means and a foot-operated member for governing said controlling means, of an air-brake-controlling valve having a horizontally-extending operating stem, 70 and means for mechanically connecting said member with said stem.

7. In a vehicle, the combination with an electric controller and brake-controlling means located in substantial axial alinement therewith, of intermediately located foot-operated means for concurrently actuating said controller and said brake-controlling means. 75

8. In a vehicle, the combination with a multi-position electric controller and an air-brake-controlling valve located in substantial axial alinement therewith, of an intermediately located foot-operated member for concurrently actuating said controller and said valve through the various positions thereof. 80

9. In a vehicle, the combination with a multi-position electric controller having an operating shaft and brake-controlling means having an operating member extending in substantial axial alinement with said shaft, 85 of means for mechanically connecting said shaft and said operating member, and foot-operated means secured to said shaft.

10. In a vehicle, the combination with a multi-position electric controller having a 90 horizontally-extending operating shaft, of an air-brake-controlling valve having a horizontally-extending operating stem, of means for mechanically connecting said shaft and said stem, and a foot-operated member secured to said shaft. 100

11. In a vehicle, the combination with electric controlling means and operating means for governing said controlling means, of air brake-controlling means located in substantial axial and horizontal alinement with said operating means to be actuated thereby. 105

12. In a vehicle, the combination with electric controlling means and body-operated means for governing said controlling means, of an air-brake-controlling valve located in substantial horizontal axial alinement with said body-operated means to be actuated thereby. 110

In testimony whereof, I have hereunto 115 subscribed my name this 16th day of May, 1919.

JOHN S. McWHIRTER.
